UNITED STATES PATENT OFFICE.

JOHN P. HENRY, OF COPPERHILL, TENNESSEE

RAIL-SUPPORTING MEANS.

1,259,096.

Specification of Letters Patent. Patented Mar. 12, 1918.

Application filed October 17, 1917. Serial No. 197,112.

To all whom it may concern:

Be it known that JOHN P. HENRY, a citizen of the United States, residing at Copperhill, in the county of Polk and State of Tennessee, have invented certain new and useful Improvements in Rail-Supporting Means, of which the following is a specification.

This invention relates to rail supporting means, and more particularly to a tie and a supporting carriage so related as to support and secure a rail in proper position for use.

One of the main objects of the invention is to provide a tie which may be readily cast from metal at comparatively small cost and rail supporting carriages slidably mounted on this tie and adjustable toward and away from each other so as to permit the gage of the road to be varied. Another object of the invention is to provide a tie and a carriage slidably thereon and so connected to the tie as to securely brace the same against lateral spreading. Further objects will appear from the detailed description.

In the drawings:

Figure 1 is a top plan view of a tie and supporting carriages mounted thereon constructed in accordance with my invention.

Fig. 2 is a side view of the same.

Fig. 3 is a view similar to Fig. 1 with the cover plates of the tie removed.

Fig. 4 is a section taken substantially on line 4—4 of Fig. 3.

Fig. 5 is a section taken on line 5—5 of Fig. 3.

Fig. 6 is a section taken on line 6—6 of Fig. 4.

Fig. 7 is a view similar to Fig. 1 of a modified form of tie, the cover plates of one section of the tie being removed as indicated by line 7—7 of Fig. 8.

Fig. 8 is a side view of the form shown in Fig. 7 one section of the tie being shown in central vertical section.

The tie A is of rectangular cross section having the bottom plate 1 and side plates 2 and 3 all cast integral. Side plate 2 is provided, adjacent each end and at its upper edge, with integral inwardly and outwardly extending flanges 4 and 5, respectively. Side plate 3 is also provided, adjacent each end, with flanges 6 and 7 corresponding to the flanges 4 and 5. These flanges and the side plates co-operate to provide approximately T-shaped guide members formed in-

tegral with the tie. These guide members fit snugly into T-channels or guide slots formed adjacent each end of a rail supporting carriage 8 slidably mounted on the upper face of the tie. This carriage is composed of two sections 9 and 10 which are movable toward and away from each other. Section 9 of the carriage is provided, at each end, with an integral outwardly extending ear 11 which is in alignment with a corresponding ear 12 formed on the section 10. The ears 11 and 12 are provided with aligned bores which receive a securing bolt 13 on the inner end of which is threaded a nut 14. These bolts provide means for securing the sections of the carriage together and for forcing them toward each other. Carriage section 9 is provided, in its upper face, with a recess which receives a wooden block 15, a block 16 being mounted in a similar recess in section 10. These blocks provide cushions for the angular fish-plates 17 carried by the carriage sections. By forcing the sections of the carriage together, the fish-plates may be secured to the rail by nut and bolt means in the usual manner. By this construction, the rail may be quickly and easily secured to the supporting carriage, this carriage being slidably on the tie and, due to the co-operating T-guide members and slots, effectually secured against vertical play relative to the tie.

An adjusting screw 20 is inserted through sections 9 and 10 of the carriage 8, a securing nut 21 being threaded on this screw and bearing against the inner face of section 10. By this means, the screw co-operates with the securing screws 13 for securing the sections of the carriage in adjustment. The adjusting screw 20 extends inwardly through a block 22 formed integral with the tie and extended transversely thereof. An adjusting nut 23 is threaded on the screw 20 adjacent the outer face of block 22, a similar nut 24 being threaded on the screw adjacent the inner face of the block. By means of the nuts 23 and 24 the screws 20 may be adjusted axially, and secured in adjustment, so as to adjust the rail supporting carriage longitudinally of the tie. By this means, the two carriages for supporting the rails may be readily adjusted toward and away from each other thus permitting variation of the gage of the road and accurate adjustment to any desired gage.

In practice, the top of the tie A will be

closed by cover plates 25 mounted thereon and secured in position by means of tap screws 26 passed through the plate and threaded into apertures in the flanges 4 and 6. Each flange may be provided with a series of spaced apertures so as to permit the plate 25 to be adjusted so as to accommodate the adjustment of the rail carriage, or the plate may be made after the rail has been adjusted to the proper gage and permanently secured in position. These plates assist the screws 20 in securing the rail carriages in position.

In the form shown in Figs. 7 and 8, the tie is formed in two sections B, and C, which are secured together by a rod 27 provided at its ends with the rectangular plates 28 and 29 which are securely bolted to the inner end of the sections B and C, respectively. Each tie section is provided with a transverse block 22^a corresponding to block 22 through which is secured the adjusting screw 20. In this construction, the sections B and C may be quickly and easily disconnected so as to use but one of the sections when desired, as in crossings or similar structures. In all other respects, the construction and operation of this form is similar to that shown in Figs. 1 to 6 inclusive and previously described in detail.

What I claim is:

1. In rail supporting means, a hollow tie of rectangular cross-section having integral inwardly and outwardly projecting flanges at the upper edge of each side wall, said flanges and the side wall of the tie forming approximately T-shaped guide members, rail supporting carriages slidably mounted

on the upper face of the tie and provided with T-guide channels receiving said guide members, and means for adjusting said carriages longitudinally of the tie. 40

2. In rail supporting means, a hollow tie of rectangular cross section having integral inwardly and outwardly projecting flanges at the upper edge of each side wall, said flanges and the side wall of the tie forming approximately T-shaped guide members, rail supporting carriages slidably mounted on the upper face of the tie and provided with T-guide channels receiving said guide members, and means for adjusting said carriages longitudinally of the tie independently of each other. 45

3. In rail supporting means, a tie formed of two sections of rectangular cross section each having integral inwardly and outwardly projecting flanges at the upper edge of each side wall, said flanges and the side walls of the tie sections forming approximately T-shaped guide members, rail supporting carriages slidably mounted on the upper faces of the tie sections and provided with T-guide channels receiving said guide members, means for adjusting said carriages longitudinally of the tie sections independently of each other, and means for detachably securing the inner ends of the tie sections together and in spaced relation. 55

In testimony whereof I affix my signature in presence of two witnesses.

JOHN P. HENRY.
